UNITED STATES PATENT OFFICE.

WILLIAM C. McKEOWN, OF BUFFALO, NEW YORK.

DOWNDRAFT HEATER OR BOILER.

1,280,788.

Specification of Letters Patent.

Patented Oct. 8, 1918.

Application filed November 18, 1915. Serial No. 62,130.

To all whom it may concern:

Be it known that I, WILLIAM C. McKEOWN, a citizen of the United States, residing at Buffalo, in the county of Erie and 5 State of New York, have invented certain new and useful Improvements in Down-draft Heaters or Boilers, of which the following is a specification.

My invention relates to a down-draft 10 heater or boiler, and more particularly to a sectional down-draft heater or boiler.

The primary object of my invention is the provision of a heater or boiler having its fire-place in the upper portion thereof 15 so that fuel is fed thereto through the top wall.

Another object is to provide internal air 20 feeding means within the fire-place and to so construct said means that it will distribute the air to the burning fuel to insure an enlivened fire throughout the full width of the fire-place.

Other objects are to simplify the construction of sectional heaters or boilers and 25 to so arrange the draft and smoke passages that the products of combustion take a circuitous course downwardly, winding around water tubes arranged in staggered relation and having a cross sectional formation providing maximum superficial area of exposure of surface to the quantity of water 30 circulating therethrough.

Another object is to provide means for creating an upward draft directly into the 35 smoke stack to assure a quick start of the fire and to enliven the fire after the same has been checked for a period of time.

With these and other objects in view, my 40 invention consists in a sectional heater or boiler having its fire-place at its upper end and circuitous draft or heat passages trending downwardly from the fire-place.

It further consists in a heater or boiler 45 having means for concentrating air at a central point within the fire-place so that fuel is supplied with air at points where ordinarily there is a deficiency of air.

It further consists in the novel features 50 of construction and in the arrangement and combination of parts to be hereinafter de-

scribed and particularly pointed out in the subjoined claims.

In the drawings,—

Figure 1 is a front elevation of my improved heater or boiler.

55

Fig. 2 is an enlarged vertical longitudinal section taken on line *a*—*a*, Fig. 1.

Fig. 3 is a detached perspective view of one of the intermediate sections of the heater or boiler.

60

Fig. 4 is a horizontal section taken on line *b*—*b*, Fig. 2.

65

Fig. 5 is a vertical transverse section taken on line *c*—*c*, Fig. 2, the smoke stack and direct up-draft stack being shown projecting upwardly from the heater or boiler.

65

Fig. 6 is a vertical longitudinal section taken on line *d*—*d*, Fig. 5.

70

Fig. 7 is an enlarged transverse section through the air concentrating or distributing device.

70

Fig. 8 is a perspective view of the front section of the heater or boiler.

75

Fig. 9 is a perspective view of the rear section.

75

Fig. 10 is a horizontal section taken on line *e*—*e*, Fig. 2.

80

Reference being had to the drawings in detail, like numerals refer to like parts in the several figures.

80

The heater or boiler comprises a front section 10, a rear section 11, and one or more intermediate sections 12, these sections being provided with water spaces or passages for the retention and circulation of water therethrough. The external contour of these sections may be varied without departing from the principle involved, and in the particular embodiment of my invention shown, the sections have vertical side edges at intermediate portions, as at 13, which flare outwardly at their upper and lower ends, as at 14, 15, respectively. The upper edges of the front and rear sections incline upwardly and inwardly from the side edges, as at 16,

85

to provide a crowning upper surface. The upper edges of the front and rear sections incline upwardly and inwardly from the side edges, as at 16, 95 to provide a crowning upper surface.

90

The front section 10 is made hollow to provide a water space 17 formed between the edge walls of the same and the front wall or outer wall 18 and rear or inner 100

wall 19. The rear or inner wall of said front section has hollow vertically-disposed ribs 20 arranged at its side marginal portions, and said wall also has a vertically-disposed hollow rib 21 arranged medially between said marginal ribs. Said wall further has hollow transverse connecting ribs 22 formed thereon which extend from the medial rib 21 to the marginal ribs 20. The ribs 22 are inclined upwardly from the medial rib 21 to the marginal ribs 20. The hollow ribs 20, 21, and 22 form extensions of the water space 17 in the front section and they are substantially of V-formation, as clearly shown in Figs. 4 and 6. The upper ends of the hollow marginal ribs 20 of said front section terminate in circular bosses 23 having nipple openings 24 formed therein. These hollow marginal ribs terminate a distance from the lower end of the front section and beneath the point of such termination said front section is provided with marginal flanges 25, the outer faces of which are continuations of the outer faces of said marginal hollow ribs.

As clearly shown in Figs. 6 and 8, the upper and lower connecting ribs of the front section have less projection from the rear or inner wall of said section than the remaining connecting ribs, for a purpose to appear hereinafter, and in order that access may be gained to the interior of the heater or boiler at different points beneath the fire-place, openings 26 are formed therethrough which are closed by doors 27 hinged or otherwise substantially fastened so that they may be conveniently opened when desired. It is to be noted that portions of the vertical rib 21 and the connecting ribs 22 extend across said openings and at these points are in the form of tubes.

The bottom of the medial hollow rib 21 terminates in a circular boss 28 having a nipple opening 29.

45 The rear section 11 is also made hollow and provided with a rear or outer wall 30 and a front or inner wall 31. These walls with the edge walls of the section form a water space 32. Extending forwardly from the side marginal portions of this section are hollow vertically-disposed ribs 33 terminating at their upper ends in circular bosses 34 having nipple openings 35 formed therein. These ribs, like the side marginal ribs of the front section, terminate short of the lower end of the section and beneath the points of such termination said section has forwardly extending marginal flanges 36.

Said front or inner wall also is provided 60 with a medially-disposed vertical hollow rib 37 which is connected with the side marginal ribs by hollow transverse connecting ribs 38. Said connecting ribs are inclined upwardly from the medially-disposed rib 37 to the side marginal ribs 33. The medially-disposed ribs

of the front and rear sections terminate with their lower ends at a point above the lower end of said sections on which they are formed and at their upper ends a considerable distance below the upper ends of said sections. The upper and lower connecting ribs 38 of said rear section have less projection from the front or inner wall of said section than the remaining connecting ribs, for a purpose to appear hereinafter. 70

The intermediate section, or each of them, if more than one are used, comprises two hollow upright side members 39 terminating in thin solid legs 40 at their lower ends and in circular bosses 41 at their upper ends having nipple openings 42. Arranged medially between the hollow side members 39 is a vertically-disposed hollow member 43 which is connected with said side members by hollow transverse members, preferably upwardly and outwardly directed connecting members 44. With the exception of the uppermost and lowermost connecting members they are preferably triangular in cross section and arranged in staggered relation, successively. The intermediate triangular connecting members are one-half the depth of the side members and the medial member and are arranged alternately at opposite sides of a plane passing transversely through the section. The upper and lower connecting members, however, are arranged uniformly between the front and rear edges of said side members, the upper connecting members being of the same depth as the side members and having notches 45 formed in their edges. The lower connecting members are of somewhat less depth than the side members and at the point where the lower member meets the medially-disposed vertical member, a circular boss 46 is formed which is provided with nipple openings 47. This boss is, therefore, at the lowest point of the water contained within the several hollow sections of the boiler. 95

100 The exterior outline of the intermediate section or sections are similar to those of the front and rear sections, except that the upper ends of the side members are disconnected, and like the medial vertically-disposed ribs of the front and rear sections, the medially-disposed member of each of the intermediate sections terminates at its upper end at a point a considerable distance from the upper end of the section of which it forms part while 105 the lower end of said medially-disposed member terminates in a plane a distance above the lower ends of the legs 40.

110 When assembling the sections of a heater or boiler the intermediate section or sections, as the case may be, are interposed between the front and rear sections, or between the "end sections" as they may be termed, with the connecting bosses at the upper ends of adjoining sections in aline- 120 125 130

ment and the lower connecting boss of the intermediate section or each of the intermediate sections in alinement with the lower circular bosses of the front and rear sections. The sections are connected together in a steam and water tight manner by means of push nipples 48 which enter the nipple openings of the circular bosses; and if desired, the sections may be otherwise connected by additional means, such as tie bolts or the like, as commonly practised in the art.

With the sections assembled, the upper connecting members 44 of the intermediate sections lie in contact with each other but are out of contact with the upper hollow connecting ribs 38 of the front and rear sections. The notches formed in said upper connecting members form draft openings between said members and a draft passage 49 is provided between the upper ribs 38 of the front and rear sections and the upper connecting members of adjoining intermediate sections, due to said ribs 38 having less projection from the inner walls of said front and rear sections than the remaining ribs thereon. The lower connecting member of the intermediate sections, as shown in Fig. 6, are arranged in line with the lower connecting ribs of the front and rear sections and are spaced from each other to provide draft passages 50. With the remaining connecting members of the intermediate section or sections staggered and the remaining connecting ribs of the rear section out of horizontal alinement with those of the front section, numerous transverse water bars separated by winding passages are provided in the space between the upper connecting members and the lower connecting members. The upper ends of the several intermediate sections are closed with a cover plate 51 provided with a fuel feed opening 52 and a smoke or draft opening 53, the fuel feed opening being closed by a hinged cover 54.

The upper connecting members of the intermediate sections and the upper hollow connecting ribs on the front and rear sections are spaced a considerable distance from the cover plate, as clearly shown in Fig. 5, and as said connecting members and ribs are inclined upwardly and outwardly and the upper ends of the intermediate sections also trend outwardly, a substantially V-shaped chamber 55 is provided in the upper end of the heater or boiler. This chamber serves as the fuel chamber or fire-place and consequently the upper connecting members of the intermediate sections and the upper hollow connecting ribs of the front and rear sections serve as hollow grate bars which lie in contact with each other at points between the notches formed therein, or are spaced, as hereinbefore described.

Beneath the lower connecting bars of the

intermediate section and the lower hollow connecting ribs of the front and rear sections, an ash pit or chamber 56 is formed, the legs 40 of the intermediate sections and flanges 25 and 36 of the front and rear sections, respectively, serving as the side confining walls of said ash pit or chamber. The front wall of the front section is provided with an opening 57, by means of which access may be gained to the ash pit, and this opening is closed by a door 58.

The rear wall of the rear section has a smoke and draft opening 59 formed therein near its lower end, and a main smoke stack 60 is connected thereto, said stack being 80 therefore in direct communication with the ash pit. A secondary smoke stack 61 is attached to the cover plate 51 so as to communicate with the fire-place through the opening 53 of said plate, said secondary 85 smoke stack being connected with the main smoke stack 60, as at 62, and having a damper 63 therein.

Arranged lengthwise in the fire-place is a hollow air feeding or distributing cylinder 64 which is preferably formed of sections 65, 66, 67 and 68, the sections 65 and 68 being co-extensive with the projecting ribs on the front and rear sections, and the sections 66 and 67 being co-extensive with 95 the intermediate heater or boiler sections. It is of course understood that when a single intermediate heater or boiler section is used in connection with the front and rear heater or boiler sections, either section 66 100 or section 67 is dispensed with, and when more than two intermediate sections are inserted between the front and rear sections, additional cylinder sections are required, corresponding in number to the additional 105 heater or boiler sections used.

Each of these cylinder sections is provided with a hub portion 69 and arms 70 connecting the hub portion with the peripheral wall of the section. A shaft 71 is 110 passed through the hubs of several cylinder sections and is journaled or supported in the front and rear heater or boiler sections, as at 72, 73. A portion of the space between the inner and outer walls of the rear sections is separated from the water space 32 of said section by a circular partition or wall 74 forming an air passage 75 between said walls, and said inner and outer walls are provided with air openings 76 which 115 lead the atmospheric air from the exterior of the heater or boiler into the hollow air-feeding cylinder, the air passing from the air openings 76 in the outer wall through the air space 75 to and through the air openings 76 in the inner wall of said rear section.

As shown in Fig. 2, a dished cover plate 77 is secured to the outer wall of the rear section and covers the air openings 76 130

formed therein. This cover plate is provided with openings 78 and a damper 79 is rotatably mounted on said cover plate and adapted to entirely close the openings in 5 said plate or open the same to any desired extent, depending on the amount of air adapted to be fed to the hollow air-feeding cylinder.

Each of the several sections of this hollow air-feeding cylinder is provided with 10 air escape openings 80 over which hoods 81 are applied which are cast or secured to said sections in any approved manner, the edges of the hoods being spaced from the peripheral wall of the cylinder sections so that air may escape through the openings in said walls to feed the fuel surrounding the cylinder with the necessary quantity of air, but prevent fuel entering said cylinder. This 15 cylinder, as shown in Fig. 5, is centrally-disposed and completely surrounded by a fuel space, the fuel being introduced through the fuel feed opening 52 in the cover plate so as to completely embed said cylinder. By 20 reason of having internal air feeding means within the fuel chamber or fire-place, air is fed to all parts of the fuel and particularly to the center of the bed of fuel, which in 25 heaters or boilers now in use is invariably 30 deficiently applied with air.

The fuel is placed in the fire-place and onto the fire-grate formed by the uppermost connecting members and ribs of the heater or boiler sections and it is ignited in any 35 suitable manner. When starting a fire the damper 63 in the secondary smoke stack is opened so that the draft is upwardly and directly out through the top of the heater or boiler. This draws the air through the 40 air openings 76 and passage 75 in the rear heater or boiler section and through the air distributing cylinder, and when the damper in the dished cover plate 77 is full open, the fuel is quickly ignited. The damper 63 in the secondary smoke stack may then be 45 closed, after which the draft is downward through the heater or boiler by reason of the draft in the main smoke stack drawing through the ash pit and through the heat-absorbing space 81 having the hollow connecting members and ribs disposed therein. The air being drawn through the distributing or air-feeding cylinder causes the fuel to be supplied with air at all points surrounding said cylinder, and as the products 50 of combustion are drawn downwardly through the fire-grate and the passages between the hollow connecting members and ribs beneath the fire-grate, the water circulating through said members and ribs is 55 thoroughly and quickly heated.

It is to be noted that by placing the lower means of connection between the several heater or boiler sections at the lowermost 60 point which the water within said sections

reach, a perfect circulation of water through the heater or boiler is provided for. The freedom of the circulation being further added to by reason of the medial vertically-disposed ribs on the front and rear 70 sections and the medial vertically-disposed members of the rear sections permitting the water as it becomes heated to travel upwardly without deviation and laterally and upwardly through the connecting members 75 and the connecting ribs. The hot water or steam, as the case may be, passes out through a pipe 82 connected to the heater or boiler at a high point, and the cold water after passing through the heating system of a 80 building returns to the boiler through the pipe 83 connected thereto at a low point.

By reason of the intermediate connecting members being triangular, a comparatively small water passage is formed therethrough 85 while the three walls of the triangle provide maximum exposure or heating surface. In this connection it may be stated that the side members of the intermediate section or sections are also made triangular in cross 90 section, as shown in Fig. 4, which greatly reduces the water capacity in said members and increases the heating surface over the straight sided surfaces now in use.

In accordance with the provisions of the 95 patent statutes, I have described the principle of operation of my invention together with the means which I now consider to represent the best embodiment thereof, but I desire to have it understood that the heater 100 or boiler shown is only illustrative and may be modified without departing from my invention or sacrificing any of the advantages thereof.

Having thus described my invention, what 105 I claim is,—

1. A down-draft heater or boiler comprising hollow end sections, each having a water space therein, and an intermediate section or sections, all sections being connected to form 110 a fire-place at the upper end of the heater or boiler, one of said end sections having an air space therein near its upper end separated from its water space and the intermediate section or sections having hollow transverse water members beneath said fire-place, and a hollow air distributing member arranged centrally within said fire-place to enable the fuel in the fire-place to entirely surround the same, the interior of said air distributing member being in communication with the outer air through said air space. 115

2. A down-draft heater or boiler having hollow end sections and an intermediate section or sections, a fire-place suitably formed 120 by said sections at the upper end of the heater or boiler, said intermediate section or sections having hollow transverse water members beneath said fire-place, a hollow air distributing member arranged centrally 125

- within said fire-place having air escape openings and adapted to have at least its lower portion embedded in the fuel, an air passage through one of said end sections 5 leading to said air distributing member, and means on said end section for regulating air passing into said air distributing member.
3. A sectional heater or boiler having a fire-place at its upper end, an ash pit at its 10 lower end, and hollow water members arranged in the space between said fire-place and ash pit, said water members being arranged in two sets on each section and being inclined upwardly from a medial line passing vertically through said heater or boiler, the water members of one set of each section being spaced from those of the other and alternating therewith.
4. A sectional heater or boiler comprising 20 a front section, a rear section and an intermediate section or sections, said front and rear sections being hollow and having oppositely-disposed hollow side ribs and connecting ribs connecting said side ribs, said 25 intermediate section or sections having hollow side members and hollow transverse members connecting said side members, the connecting members of the intermediate section or sections being disposed in two sets 30 with the connecting members of the two sets in different vertical planes and arranged alternatively from top to bottom and a smoke stack connected at a low point of said heater or boiler.
- 35 5. A down-draft heater or boiler comprising hollow end sections and hollow intermediate sections, said end sections having spaced inner and outer walls and each of said intermediate sections having hollow 40 vertically-disposed side members terminating in solid legs at their lower ends, a hollow vertically-disposed medial member somewhat shorter than said side members and upwardly and outwardly inclined superposed connecting members connecting said medial member with said side members, the uppermost connecting members serving as hollow fire bars and a cover plate closing the 45 upper end of the heater or boiler and receiving support from the upper ends of said side members and from the upper ends of said end sections.
6. A heater or boiler comprising hollow end sections having spaced inner and outer 55 walls, the inner wall of each of said sections being provided with hollow marginal side ribs terminating at their upper ends in circular bosses and having also a vertically-disposed medial hollow rib and upwardly and 60 outwardly directed hollow connecting ribs connecting said medial rib with said side ribs, the medial hollow rib of each of said sections terminating at its lower end in a circular boss, an intermediate section comprising hollow side members terminating at 65 their upper ends in circular bosses arranged in line with the circular bosses at the upper ends of the side marginal ribs of said end sections, said intermediate section having also a hollow vertically-disposed medial 70 member and upwardly and outwardly directed hollow connecting members extending from said medial member to said hollow side members, said hollow medial member having a circular portion at its lower end 75 alined with the circular bosses at the lower ends of the medial hollow ribs of said end sections, nipples connecting alined circular bosses of adjoining sections, a smoke stack in communication with the space below the 80 lowermost connecting member of said intermediate section, and a cover plate closing the upper end of said intermediate section and being spaced from the uppermost connecting member of said intermediate section or 85 sections to provide a fire-place between the two.
7. A sectional heater or boiler having end sections, and intermediate sections provided with hollow side members and connecting 90 members extending upwardly and outwardly from a vertical plane passing medially between said side members, the connecting members of each intermediate section being arranged from top to bottom in staggered 95 relation, and the uppermost connecting members serving as fire bars and forming a fire-place having a fire-grate sloping from opposite walls.
8. A heater or boiler comprising end sections and intermediate sections, each intermediate section having hollow side members, a hollow vertically-disposed medial member and a series of connecting members extending outwardly and upwardly from 100 said medial member to said side members, said connecting members being of less depth than said side members and alternately arranged at opposite sides of a plane passing centrally and transversely through the intermediate section to form circuitous downwardly trending draft passages, the connecting members terminating a distance from the upper and lower ends of said sections to provide a fire-place space at the upper end 105 of the heater or boiler and an ash pit at the lower end thereof, a smoke stack in communication with the ash pit, and means for closing the upper end of the heater or boiler.
9. A sectional heater or boiler comprising 110 connected hollow sections, adjacent sections having communication with each other at their upper corners and also at a medial low point, said sections being constructed to permit the water to travel upwardly from said 115 medial low point and also laterally in a gradually rising course.
10. A sectional heater or boiler comprising end sections and intermediate sections, each of said intermediate sections compris- 120
- 125
- 130

ing hollow side members terminating in solid legs at their lower ends, a vertically-disposed medial member and connecting members for each intermediate section arranged in two sets and extending from said medial member upwardly and outwardly to the two sets of side members, said connecting members of each intermediate section being

of triangular formation in cross section and reversely arranged with those of one set alternating with those of the other, one of said end members having a series of openings permitting access to the several connecting members, and closures for said openings.

In testimony whereof I affix my signature. 15

WILLIAM C. McKEOWN.
